UNITED STATES PATENT OFFICE.

OTTO SCHÖBE, OF HALLE-ON-THE-SAALE, GERMANY.

GRINDING-TONGS FOR SPIRAL DRILLS.

No. 891,738.

Specification of Letters Patent.

Patented June 23, 1908.

Application filed September 28, 1906. Serial No. 336,644.

To all whom it may concern:

Be it known that I, OTTO SCHÖBE, subject of Emperor of Germany, residing at No. 13 Zinksgartenstrasse, Halle-on-the-Saale, Germany, have invented new and useful Improvements in Grinding-Tongs for Spiral Drills, of which the following is a specification.

It is the object of my invention to provide means for holding the spiral drills while being ground or sharpened. In grinding spiral drills as heretofore practiced, as is well known, it has been difficult to grind the cutting faces uniformly, and it frequently happens that the drill is torn from the operator's hand while being ground and the cutting face which has already been ground is thus destroyed.

The present invention comprises means for positively gripping the spiral drills and pattern means having a profile corresponding to the shape which the spiral drill must have when ground.

The invention consists in the features and combination and arrangement of parts hereinafter described and particularly pointed out in the claims.

In the accompanying drawings,—Figure 1 is a front view of the invention, Fig. 2 is a side view looking from the right of Fig. 1. Fig. 3 is a rear view, and Fig. 4 is a side view looking from the left of Fig. 1.

The appliance is in the form of a pair of tongs, the lever arms of which are indicated at *c*. These are pivoted together at *c'* and they have opposing jaws *a* and *b*. These jaws are guided one by the other, the jaw *b* having a tongue *b'* to enter a slot or groove *a'* in the jaw *a*. Each jaw has a recess *d* adapted in shape for securely holding the drill during the grinding operation, it being

understood that the operator grasps the levers or handles *c* and thus exerts the required degree of pressure for holding the drill firmly between the jaws *a* and *b*. Associated with these gripping jaws is the grinding pattern *g*. This is held in proper position by means of arms *e* and *f* which are movably secured to the said jaws so as to allow movement of the latter in opening and closing. This pattern plate has a profile corresponding to that required for the grinding true of the spiral drill on both sides. In the use of the appliance the drill *h* is held by the jaws of the tongs with the drill having its cutting edge fitted into the pattern as indicated in Figs. 1 and 4, and by this means the grinding is performed while the drill is held securely in place and in connection with the pattern.

I claim as my invention:

1. An appliance for holding spiral drills while being ground comprising a pair of tongs having jaws which have a tongue and groove connection between them, said jaws being adapted to grip the drill and a pattern plate corresponding in profile to the drill to be ground, and two movable arms for holding the plate in position, substantially as described.

2. An appliance for holding spiral drills comprising the tongs for gripping the drills, the pattern member and the movable arms connecting the pattern member to the jaws of the tongs.

In testimony whereof I have signed my name to this specification in the presence of two subscribing witnesses.

OTTO SCHÖBE.
